UNITED STATES PATENT OFFICE.

CHARLES DIETRICK, OF PITTSBURGH, PENNSYLVANIA.

BASEBALL GAME.

Application filed October 1, 1921. Serial No. 504,745.

To all whom it may concern:

Be it known that I, CHARLES DIETRICK, a citizen of the United States, residing at Pittsburgh, in the county of Allegheny and 5 State of Pennsylvania, have invented new and useful Improvements in Baseball Games, of which the following is a specification.

This invention relates to games and more 10 particularly to what I term a base ball game.

One of the main objects of the invention is to provide a game of the character stated, which will closely approach the well known game of base ball in the various plays made, 15 and will present a neat and attractive appearance.

A further object is to provide a device which may be readily produced and sold at a reasonable cost. Further objects will appear from the detailed description.

In the drawings:—

Figure 1 is a top plan view of the device.

Figure 2 is a similar view, parts being removed.

Figure 3 is an underneath plan view.

Figure 4 is a side view.

Figure 5 is an end view.

Figure 6 is a fragmentary sectional view.

Figure 7 is a fragmentary detail of the 30 shutters and associated parts.

Figure 8 is a diagram of the light-controlling circuits.

The device includes a board or base 1 of 35 rectangular shape, provided with side rails 2 and an end rail 3, this base in practice being supported at an inclination with end rail 3 at the lower end of the base. At the upper end of the base 1, I provide a housing 4 which is divided into a plurality of 40 compartments within each of which is mounted an electric light globe 5, these globes being differently coloured so as to produce a variegated lighting effect when illuminated.

45 A strip 6 is secured to the upper face of base 1 in parallel spaced relation to one of the side rails 2, this strip forming with the side rail means for receiving and guiding the plunger of a spring catapult 7 of any known or approved type. In practice, a suitable spherical object, such as a marble, is placed in the space between strip 6 and rail 2, this object being discharged by the catapult against a curved plate 8 secured 50 between side rails 2 adjacent to the upper end of base 1. A tapering cushion mem-

ber 9 of rubber or other suitable elastic material is secured centrally of plate 8 and serves to direct the ball or marble toward pins 10, which are secured in the upper face 60 of base 1 in staggered relation, the pins being so spaced as to permit the ball to roll between the same toward the lower end of base 1. The base is further provided with three openings indicated by H, 2^b and 3^b, 65 these openings being intended to indicate the home plate, second base, and third base, respectively. A trough 11 is secured beneath base 1 and discharges into a main trough 12 positioned beneath the base 70 adjacent to the lower end thereof and inclined downwardly laterally of the base. To supplemental troughs 13 communicate with trough 11 and extend beneath the openings 2^b and 3^b. In this manner, if the ball passes 75 through any of the openings it will be directed into main trough 12 and discharged therefrom into the player's hand, which is held beneath the discharge end of the trough, as will be understood. 80

A strip 14 is secured across the lower end of rails 2 and rests upon the upper edges of the rails, this strip being held in position by means of a wing nut 15 threaded upon the upper end of a pin 16 secured in base 85 1. A plurality of metallic angle strips 17 are secured to the under face of strip 14, these angle strips being positioned in alignment with corresponding spaces into which the upper face of strip 14 is divided, these 90 spaces being marked to designate the various possible plays. The strips 17, which constitute contact strips, are positioned in alignment with metallic plates or shutters which are loosely mounted at their upper ends 95 upon a metallic rod 19 which is secured through eye members 20. Members 20 are secured in a closure member or door 21, which is hingedly secured at 22 to base 1, this door being positioned above trough 12. 100

A wire spring 23 is secured to base 1 and serves to hold the door in raised or closed position. For opening the door I provide a pull rod 24 which is secured at its inner end to an eye 25 secured in the door, this rod 105 being slidable through an aperture provided in the front wall of trough 12. An electric conductor 25 is connected to one leaf of one of the hinges 22, the other leaf of this hinge being connected by a lead 26 to one of the 110 eye members 20^a through which rod 19 passes. The other end of wire 25 is con-

2

nected to one terminal of a socket 27 of standard type, the other terminal of this socket being connected by a wire 28 to one pole of the lights or globes 5. The other 5 side of these globes is connected by wires 29 to angular contact strips 17. The lights may be connected to the contact strips 17 in any suitable or preferred manner, as will be understood, so that when one of the shutters 10 18 is rocked rearwardly into contact with the corresponding strip 17, the circuit of one of the lights 5 will be closed, thus illuminating the light. In practice, the ball passes through the pins 10 and strikes one 15 of the shutters, rocking the same into contact with the corresponding strips 17 and closing the circuit of one of the lights, strip 17 serving to limit rear movement of shutter 18 so that the ball is held upon the upper 20 face of door 21. By rocking the door downwardly, the ball is discharged into trough 12 and may be readily recovered in the manner previously described. The play made is noted, and the player who has the greater 25 number of runs after each player has shot nine times is considered as winning the game. As will be understood, in the event that neither player has scored or the score is a tie, after each has shot nine times, the 30 playing is continued until one of the players makes an additional score, thus winning the game.

What I claim is:—

1. In a device of the character described, 35 an inclined base, a downwardly opening door hinged to said base at the lower end there-

of, shutters mounted above the door for swinging movement, means for limiting outward movement of the shutters, a main trough positioned beneath said door, a 40 trough discharging into said main trough, supplemental troughs communicating with the second mentioned trough, the base being provided with openings communicating with said second mentioned trough and the supplemental troughs, and means for normally holding said door raised.

2. In a device of the character described, an inclined base provided with an opening 50 adjacent to its lower end, a closure member for said opening hingedly secured to the base at the lower edge of the opening, means for normally holding said member raised, supporting members carried by the closure member, a rod of electrical conducting material carried by the supporting members, shutters of electrical conducting material mounted at their upper ends on said rod for free swinging movement, contact members mounted in rear of said shutters for 55 limiting rearward movement thereof, electrically actuated signaling means, the contact members being electrically connected to one side of the signaling means, and means for connecting said rod to one pole of a 60 source of electricity and for connecting the other side of the signaling means to the other pole of said source of electricity.

In testimony whereof I affix my signature.

CHARLES DIETRICK.
